UNITED STATES PATENT OFFICE.

ANIELLO SAVARESE, OF PARIS, FRANCE.

MACHINE FOR CASTING TYPE.

1,100,495.

Specification of Letters Patent. Patented June 16, 1914.

Application filed May 7, 1912. Serial No. 695,687.

To all whom it may concern:

Be it known that I, ANIELLO SAVARESE, of Paris, France, a subject of the King of Italy, have invented certain new and useful Improvements in Machines for Casting Type, of which the following is a full, clear, and exact description.

The present invention relates to improvements in type casting machines of the Foucher type, the object of my invention being to adapt a machine of this character to the casting of type of the peculiar construction employed in the composing machines of the character shown in the Savarese Patent 920,086 and Serial No. 695,686.

Type-casting machines of the Foucher construction comprise as is well known, a movable plate which forms the bottom of the type casting mold and which ejects the type after it has been cast. As it leaves the mold, the type is seized between the two jaws of a gripping device, which travels it over the table of the machine and passes it between trimming knives. During this movement the type is pressed against the bed of the machine by a movable counter plate arranged between the jaws of the gripping device.

The present improvements comprise, (1) the arrangement in connection with the movable bottom plate of the mold, of a core which serves to produce a recess in the shank of the cast type so that the latter is given a bifurcated construction. (2) The arrangement, on the lower face of the counter-plate, of a projection which serves as a core engaging between the legs of the cast type and preventing the deformation of the latter by the gripper and the trimming knives. (3) The arrangement, at the end of the bed of the machine, of a gage on which the type are threaded by the gripper and which trims the sides of the type. Passing the gage, the finished type run on a receiving rail which threads them directly upon a magazine rail for charging the composing machine, the magazine rail being arranged in extension of the receiving rail of the casting machine.

In the accompanying drawing, Figure 1 is an elevation, partly in section, of the casting machine; Fig. 2 is a perspective of a cast type, drawn to a larger scale; Fig. 3 is a side elevation of the movable bottom plate of the mold, the core carried thereby and the superposed counter-plate; Fig. 4 is a section on the line 4—4, Fig. 3; Fig. 5 is a

perspective, partially broken away, showing the gage; Fig. 6 is an elevation of the gage; Fig. 7 is a plan of the same; Fig. 8 is a detail of the gage; and Fig. 9 is a plan corresponding to Fig. 8.

The movable plate *a* which constitutes the bottom of the mold, is mounted in usual fashion, at the upper end of the arm *a*¹, to which vertical movement is imparted by the cam *a*² on the driving shaft *A*. The plate is made fast to the arm *a*¹ by a bar *a*³ which engages in the aperture *a*⁴ (Fig. 3) in the plate *a*. The downward travel of the plate *a* is limited by the adjustable stop *i*. The core *b* is mounted in fixed position on the bed of the machine by a screw *b*¹ the shank of which passes through the aperture *b*² in the lower portion of the core. A large aperture *a*⁵ in the movable plate *a* accommodates the lower portion of the core *b*, the upper portion of the latter passing through the face of the plate *a* and being shaped to impart the desired bi-furcate form to the shank of the cast type.

During the casting of a type (Fig. 1) the core *b* extends above the face of the plate *a* the thickness of the type. After the casting, the plate *a* rises and slides the cast type up and off of the core *b* into position to be picked up by the gripper *d*. The latter, which is of common construction, seizes the type between the jaws 1 and 2. At the same moment the counter-plate *f* is lowered and the core *f*¹ thereon enters between the legs *x*¹ of the type stem, and so prevents the deformation of the type under the pressure of the jaws of the gripper. The latter moves the type on the table *e* of the machine in the direction of the arrow *y*, passing it in contact with the usual trimming knives (not shown). During this movement of the type it is pressed down on the table by the counter plate *f* and the core *f*¹ thereon likewise prevents deformation of the type by the trimming knives. When the gripper *d* arrives at the end of the table *l*, the counter plate *f*, being depressed still further, pushes the type out of the gripper and forces it on the broach *g* and the gage *g*¹, which forms a continuation of the latter. As it descends the gage *g*¹, the narrow sides of the type are engaged by the oblique trimming knives *g*² carried by the bars *g*³. Between the bars *g*³ is arranged a spacing member *g*⁴ by which the space between the latter is determined.

Immediately below the gage *g*¹ is a slide rail

h which forms a continuation of the beaded rail *h*¹. The finished type slide down these rails and directly upon the magazine charging rails (not shown) which are removably mounted in extension of the rail *h*¹. The magazine rails, after being filled with type are carried to the composing machine and used to charge the magazine rails of the latter.

10 I claim as my invention:—

1. A type casting machine comprising a gripper for removing the cast type and between the jaws of the gripper a movable member having a downward extension forming a core for the type to prevent injury to the latter during its engagement by the gripper.
- 15 2. A type casting machine comprising a casting mold, means for moving the cast type from the latter, a gage, means for forcing the shifted type upon the gage, a receiving rail on which the type are automatically threaded as they pass from the gage.
- 20 3. A type casting machine comprising a casting chamber having a bottom plate, a

core projecting through said plate into the casting chamber, said core being shaped to produce a bi-furcated type shank and means for moving with relation to each other said plate and core to strip the type from the latter.

4. A type casting machine comprising a casting chamber having a movable plate forming a wall of the chamber, a stationary core projecting through said plate into the casting chamber, and means for moving said plate to strip the cast type from the core, in combination with a gripper for removing the cast type and between the jaws of the gripper a movable member having a downward extension forming a core for the type to prevent injury to the latter during its engagement by the gripper.

In testimony whereof I have signed my name to this specification, in the presence of two subscribing witnesses.

ANIELLO SAVARESE.
